UNITED STATES PATENT OFFICE.

WILLIS A. BRADSHAW, OF CHARLOTTE, NORTH CAROLINA, ASSIGNOR OF ONE-HALF TO MORTIMER A. BLAND, OF CHARLOTTE, NORTH CAROLINA.

FIRE-EXTINGUISHER.

No. 881,893.

Specification of Letters Patent. Patented March 17, 1908.

Application filed November 5, 1907. Serial No. 400,842.

To all whom it may concern:

Be it known that I, WILLIS A. BRADSHAW, of Charlotte, in the county of Mecklenburg and State of North Carolina, have invented 5 certain new and useful Improvements in Fire-Extinguishers; and I do hereby declare the following to be a full, clear, and exact description of the invention, such as will enable others skilled in the art to which it applies to make and use the same.

My invention relates to an improvement in fire extinguishers.

In the portable chemical extinguishers now in use, the solution and gas, are ejected 15 in a small stream through the hose nozzle which is held in the hand and-manipulated to direct the stream against the fire.

The object of my invention is to provide means for converting the stream into a fan-like spray or curtain which will cover a 20 greater area than a single solid stream.

A further object is to provide means for automatically inverting the tank and starting the apparatus when the temperature in 25 the room, where the extinguisher is located, reaches a predetermined point.

A further object is to so construct the extinguisher that the solution ejected therefrom operates to impart a swinging motion 30 to the extinguisher thus increasing the area protected by the extinguisher.

With these ends in view my invention consists in the parts and combinations of parts as will be more fully explained and 35 pointed out in the claims.

In the accompanying drawings, Figure 1 is a view in elevation of my improvement, showing the tank in its upright position. Fig. 2 is a similar view showing it inverted. 40 Fig. 3 is a view in section through the tank and removable cap and Fig. 4 is a plan view of the latter.

1 represents a cylindrical tank preferably provided at its lower end with a flange 2 having diametrically opposed openings for the passage of the rod 3 secured to the post or wall 4. In its normal position as shown in Fig. 1 this tank 1 rests on and above the rod 3 and is retained in its upright position 45 by a wire or other device 5 having a plug that will fuse when the temperature reaches a predetermined point, and thus release the tank and permit it to swing to its inverted position as shown in Fig. 2.

55 The tank 1 is provided at its open end

with a neck 6 having an inclined ground surface 7 on which the cap 8 rests. This cap 8 is pivoted to the tank at 9, and its lower face is beveled to conform to the bevel or inclination of the outer edge of the open 60 neck of the tank, the pivot 9 being so located with reference to the beveled faces of the cap and the free edge of the neck, that when the cap is turned in a direction to open the tank, the beveled face of the head will be 65 moved away from its seat on the neck, and when turned in the opposite direction, the two ground beveled surfaces will be brought into close contact, thus forming an air tight joint between the parts.

The tank is provided internally adjacent to its neck with a tube or chamber 10, preferably made of lead, for containing a chemical. This chamber is open at its top and bottom, and is provided intermediate its ends above 70 the normal water line, with a perforated dia- 75 phragm 11 on which the acid or other chemicals or vessel containing fluid acid, or chemical rests and is also provided at its upper end with perforation 12.

When the tank is inverted the soda or other solution entering the lower end of the tube and through the perforation 12 in said tube, comes in contact with the acid or other chemical contained in the tube, thus evolving 85 a gas, which producing a pressure within the tank, forces out the water saturated with the gas, through the hose or pipe 13, connected to the tank adjacent to the upper end of the latter. The cap 8 is provided with a 90 handle 14 which, when the cap 8 is seated on the neck of the tank, is engaged by the stops 15 and held against lateral movement. One stop is necessarily movable so as to permit the cap to be turned in a direction to open 95 the tank.

The cap is provided on its top or outer face with a concaved recess 16 into which the nozzle 17 projects, the hose or pipe 15 passing through the side wall of the cap 8 so as to 100 bring the nozzle within pointing toward the concave recess, at or near the center of the cap.

With this arrangement, the solution, as it issues in a stream from the nozzle, impinges 105 against the concave face of the cap and is broken up into a fan like spray or curtain, which covers a considerably greater area than a single solid stream, thus using the solution more effectively and economically, 110

than if used in the form of a single stream. This stream impinging on the cap, together with the spray projected from the cap, causes the tank 1 to have a swinging movement on its supporting rod 3, thus covering and protecting a greater area than can possibly be covered by a fixed tank, and also covering places where it would be dangerous or impossible for a person to enter with a portable extinguisher.

With this apparatus, when the temperature reaches a predetermined point, the fuse melts, thus permitting the tank to turn from its upright to its inverted position. As soon as it is inverted, the mixture of the acid with the solution generates a gas the pressure of which forces out the solution and gas in the well known manner.

It is evident that many slight changes might be resorted to in the relative arrangement of parts shown and described without departing from the spirit and scope of my invention hence I would have it understood that I do not wish to confine myself to the exact construction shown and described, but,

Having fully described my invention what I claim as new and desire to secure by Letters-Patent, is:—

1. In a fire extinguisher, the combination with a tank having a concavity in one end, of a pipe having a nozzle the latter discharging against the curved wall of the concavity at the end of the tank in a direction at an angle to the longitudinal axis of the tank.

2. In a fire extinguisher the combination with a tank and a cap closing one end thereof the said cap having a concavity in its outer face, of a tube for discharging the solution against the curved face of the concavity in the outer face of the cap.

3. In a fire extinguisher, the combination with a tank having an open end the latter being beveled, of a cap pivoted to the tank and correspondingly beveled, whereby a

turning movement of the cap in one direction carries its beveled surface away from the seat on the tank, and a movement in the opposite direction carries its beveled face into contact with the beveled seat on the tank.

4. In a fire extinguisher the combination with a tank having a beveled seat the latter having a ground face, of a cap pivoted to the tank and having a beveled and ground face, and means for locking the cap against turning movement.

5. In a fire extinguisher the combination with a pivoted tank having a concavity in its upper end and fusible means for holding the tank in its upright position, of a discharge tube the nozzle of which projects the solution against the wall of said concavity in the upper end of the tank when the latter is inverted and in a direction at an angle to the longitudinal axis of the tank.

6. In a fire extinguisher, the combination with a pivoted tank having a concavity in its cap, and fusible means for holding the tank in its upright position, of a discharge pipe the nozzle of which discharges the solution against the face of the concavity in the cap in a lateral direction.

7. In a fire extinguisher, the combination with a pivoted tank having a beveled seat, a cap pivoted to the tank and having a beveled face adapted to make contact with the beveled seat on the tank, the said cap having a concave outer face, and fusible means for holding the tank in its upright position, of a discharge pipe the nozzle of which discharges the solution against the concave outer face of the cap.

In testimony whereof, I have signed this specification in the presence of two subscribing witnesses.

WILLIS A. BRADSHAW.
